WINDOW GLASS PACKAGE

Buster O. Salmon, Henryetta, Okla., assignor to Hoerner Boxes, Inc., Keokuk, Iowa, a corporation of Delaware
Filed Mar. 6, 1961, Ser. No. 93,569
8 Claims. (Cl. 229—51)

This invention relates to a glass package.

In the shipment of sheet glass in relatively small quantities the provision of a rigid close fitting corrugated board container has proved satisfactory. In the assembly of such a container, initially a large piece of corrugated board is folded or wrapped around the assembled sheets of glass with the folds being along the corrugated lines, and the wrapper has adhesively secured within its inside surface a rip tape which at one end is also adhesively secured to a tab formed into one of the adjoining edges of the folded wrapper, so that lifting the tab would bring with it the rip tape and make it possible to tear the corrugated board wrapper into two sections. After this board is wrapped around the assembled glass, ends for the sheath thus formed are cut from other sections of corrugated board so that the sides of the ends overwrap the ends of the initial wrapper or sheath, then the ends of the end portions are folded along the edges of the sheath at its corners a distance equal to the extension of the sides of the sheath ends over the panels of the sheath and these corner folded ends have wings extending from their free edges to fold upon the panels of the sheath. The corners of the sheath end sides have been cut angularly inwardly toward their edges from their folded corners and edges of the wings coincide with these cuts to form a firm overwrap of the ends around the edges of the ends of the sheath. These ends are tray shaped members and are adhesively secured throughout their inner surfaces to the ends of the sheath enclosing the sheet glass. The rip tape goes around the sheath between and substantially parallel to these adhesively applied ends.

This construction provides a rigid container for the initial shipment of the sheet glass and the sheet glass not presently used may be retained or stored within the container by placing thereon the severed end, severed by the tear tape, for future use.

Accordingly an object of this invention is to provide a rigid board container for the safe shipment of sheet glass. Another object is to provide for opening of such a container and providing for its possible re-use for storage. Other objects and advantages of the invention will be apparent from the following description and the accompanying drawings forming a part hereof, and in which:

FIGURE 1 is a perspective view of the container in its closed position, enclosing the sheet glass.

FIGURE 2 is a similar perspective view with one end of the container torn away by the use of the rip tape, exposing the contents.

FIGURE 3 is a perspective view of the end removed from the package shown in FIGURE 2, with parts broken away.

FIGURE 4 is a sectional view on line 4—4 of FIGURE 3 on an enlarged scale.

In the drawings similar numerals refer to similar parts throughout the several views.

Pieces of sheet glass 1 are packed together, they could be spaced by any means 2 to avoid their etching each other. Around them is placed the wrapper 3 preferably made of corrugated board with the corrugations running in line with the folds of the wrapper. This wrapper forms a sheath surrounding the contents of the package. The wrapper preferably has cuts 4 at one edge forming a tab and a rip tape 5 adhesively secured to the inside of

2

the wrapper parallel to its edge so that upon lifting the tab 4, the tab will bring with it the rip tape and so tear the sheet into two portions parallel to its length. Ends 6 preferably also of corrugated board are then folded into trough shape, and the sides 7 are adhesively secured to the sides of the panels of the wrapper or sheath 3. These ends 6 have at their ends a portion 8 folded at the corner 9 of the sheath against the sheath edge as shown at 10 and these folded portions have projecting wings 11 folded inwardly along the corners of the panels of the sheath. The sides 7 have been cut away along angular lines leading from the folded corners 9 so that the wings coincide with the ends of sides 7 so that the sheath ends form a complete tray which is adhesively secured to the ends 15 of the sheath over their complete adjoining surfaces and this renders the sheath rigid and makes it virtually impossible to twist the sheath from side to side or from corner to corner. The wings extend a distance along both panels of the sheath, to give good support to the 20 container corners.

It is preferable that the ends 6 be folded with the corrugations of the board in the sides 7 of these ends parallel to the direction of the corrugations in the panels of the sheath, as shown in FIGURE 4. The board is less 25 susceptible to cutting by the glass at the ends of the sheath across the transverse direction of the corrugations. Also in the preferred form double faced C fluted board is used and in the ends double wall BC fluted board is used also as shown in FIGURE 4, although of course 30 this preference is not essential for the success of the construction. In this preferred construction, it is apparent that the flutes in the wings extend around the sheath ends, parallel thereto, and add additional strength because of this direction of placement.

It will be apparent that when the package has been initially opened by removing the tear tape 5 by lifting the tab 4 one end with its adhesively secured portion of the sheath may be removed and the contents of the package removed. This end may be replaced over the package 40 contents remaining and if desired even the space occupied by the removed sheets of glass could be refilled by sheets of corrugated board and a firm storage package is then obtained. Of course where it is desired to increase the firmness of the package, paper tape could be adhesively wrapped around the package where the rip tape 45 had been removed. Or the glass could be removed, and treated in any desired manner and resealed for another shipment.

It will be apparent that various changes and modifications in the construction of the container above described 50 may be made without departing from the invention.

What is claimed as new and is desired to be secured by Letters Patent is:

1. A container for packaged articles such as rectangular sheets of glass and the like comprising an elongated sheet of board around one or more articles forming an open ended sheath, similar trough shaped ends adhesively secured to the outside of the ends of the sheath, each said end comprising sections of board folded around the 55 ends of the articles and sheath, forming sheath side overlaps and folded around the edges of the sheath at the corners a distance substantially equal to the side overlap of the sheath side overlaps, forming an end wrap, each sheath side overlap at its corner being cut away along 60 an angular line extending inwardly from the end wrap corner at its corner fold, the end wraps having wings extending in line with and joining the side overlaps and being adhesively secured to the folded sheath.

2. The container of claim 1 in which the free edges 65 of the board meet near the center of one side of the sheath.

3. The container of claim 1 in which the sheath side

overlaps, end wraps and wings and the sheath are adhesively secured together over their entire mutual contiguous surfaces.

4. The container of claim 1 in which the free edges of the board meet near the center of one side of the sheath, one of said edges having cuts forming an integral tab for initiating a tear to open the container, a rip tape adhesively secured around the inside of the sheath and to said tab, whereby lifting the tab brings with it the rip tape to tear the container into two portions, around the sheath between its ends.

5. The container of claim 1 in which the trough shaped ends enclosing the sheath ends are corrugated board folded around the sheath ends along lines normal to the corrugations.

6. A container for packaged articles such as rectangular sheets of glass and the like comprising an elongated sheet of corrugated board folded along its corrugations around one or more articles forming an open ended sheath, similar trough shaped ends adhesively secured to the outside of the ends of the sheath, each said end comprising sections of corrugated board folded around the ends of the articles and sheath, forming sheath side overlaps and folded around the edges of the sheath at the

5

corners a distance substantially equal to the side overlap of the sheath side overlaps, forming an end wrap, each sheath side overlap at its corner being cut away along an angular line extending inwardly from the end wrap corner at its corner fold, the end wraps having wings extending in line with and joining the side overlaps and being adhesively secured to the folded sheath.

7. The container of claim 6 in which the trough shaped ends enclosing the sheath ends are folded around the sheath ends along lines normal to the corrugations, the corrugations in the sheath side overlaps being parallel to those of the sheath.

8. The container of claim 6 in which the sheath side overlaps and sheath are adhesively secured together over their entire mutual contiguous surfaces.
